THOMAS GEORGE BAXENDEN, OF WATFORD, AND JOHN ROBERT COLLYEAR, OF BUSHEY, ENGLAND

METALLIC SPOOL

Application filed July 18, 1928, Serial No. 293,567, and in Great Britain October 7, 1927.

This invention relates to spools which are provided with central stub spindles extending beyond the outer sides of the end discs, and in particular to small spools of this kind, such as are used for photographic films.

These stub spindles at the present time are sometimes formed by extending the ends of the main spindle through the discs, or else 10 they consist of short stub spindles of tubular or solid form forced into the ends of a tubular main spindle on the extreme ends of which the discs are mounted.

According to the present invention, the 15 end stub spindles are formed of metal in one with the end discs by drawing, pressing, spinning or similar processes. The main or body part of the spool spindle which connects the end discs may be fitted thereto by 20 welding, brazing or soldering, for example, in the manner described in British Patent No. 234,610; alternatively, the ends of the main spindle may be forced into the hollow stub spindles, or connected thereto in any 25 other suitable manner.

The stub spindles or one of them may be slit or otherwise adapted to form the driving connection for the spool.

The accompanying drawing shows two 30 forms of the improved spool.

Fig. 1 is a longitudinal section showing one construction,

Fig. 2 is a part longitudinal section showing a modified construction.

35 In the construction shown in Fig. 1, the stub spindles *a* are made in one with the end discs *b* by drawing and the ends of the main spindle *c*, which is of tubular form, are welded to the end discs *b*.

40 In the construction shown in Fig. 2, the end discs *b* have the integral stub spindles drawn up from the metal thereof and the ends of the main spindle *d* are forced into the sockets formed by the hollow stub spindles for the purpose of securing the parts together.

In both constructions one of the stub spindles is slit, as at *e* to form the usual driving connection.

50 We claim—

1. A built up photographic film spool comprising in combination, a pair of metallic end discs, each disc having an integral drawn stub, the stub on one of said discs being formed with a cross slot to receive a winding key, and a tubular spindle welded at its ends to the metallic discs, the stubs of the discs projecting outwardly to form trunnions for the spool.

2. A photographic spool comprising metallic discs, a spindle formed of sheet metal rolled upon itself to provide a split tube and welded at its ends to the central portions of the discs, the discs having integral drawn trunnions extending outwardly thereof, and the spindle having a longitudinal slot between the ends of said tube to receive the end of the paper strip of a loaded photographic spool, one of the trunnions having a key receiving slot.
